SAFETY DOOR FOR FURNACES OR THE LIKE

Lemuel J. Harris, Holland, Mich., assignor to
 Holland Furnace Company, Holland, Mich., a
 corporation of Delaware

Application September 30, 1948, Serial No. 148,885

Term of patent 14 years

(Cl. D81—25)

To all whom it may concern:

Be it known that I, Lemuel J. Harris, a citizen of the United States, residing at Holland, county of Ottawa, State of Michigan, have invented a new, original, and ornamental Design for a Safety Door for Furnaces or the like, of which the following is a specification, reference being had to the accompanying drawing, forming a part hereof.

In the drawings:

Fig. 1 is a front elevational view of a safety door for furnaces or the like, showing the new design.

Fig. 2 is a top plan view thereof.

Fig. 3 is a side elevational view looking at the left hand end of Figs. 1 and 2.

I claim:

The ornamental design for a safety door for furnaces or the like, as shown.

LEMUEL J. HARRIS.
